(57) **CLAIM**

The ornamental design for a packaged medicine inspection apparatus, as shown and described.

DESCRIPTION

FIG. 1 is a top, front and right side perspective view of a packaged medicine inspection apparatus in accordance with my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a left side elevational view thereof;

FIG. 7 is a cross-sectional view thereof taken along line VII-VII of FIG. 2, in which an internal structure thereof is not shown;

FIG. 8 is a cross-sectional view thereof taken along line VIII-VIII of FIG. 2, in which an internal structure thereof is not shown;

FIG. 9 is an enlarged partial cross-sectional view of a portion defined by an arrow A and an arrow B of FIG. 7;

FIG. 10 is an enlarged partial cross-sectional view of a portion defined by an arrow A and an arrow C of FIG. 7;

FIG. 11 is an enlarged partial cross-sectional view of a portion defined by an arrow D and an arrow E of FIG. 8; and, FIG. 12 is a top, front and right side perspective view thereof in a manner of use.

The broken lines showing portions of a packaged medicine inspection apparatus in all views shown represent unclaimed subject matter and form no part of the claimed design.

The dash-dot broken lines in FIGS. 9-11 represent the boundary lines of the partially enlarged range and form no part of the claimed design.
